CRACKING AND COOKING OF HYDROCARBON OILS

Joseph Mason Barron, Port Arthur, Tex., assignor to The Texas Company, New York, N. Y., a corporation of Delaware

Application November 28, 1942, Serial No. 467,176

4 Claims. (Cl. 196—49)

1

This invention relates to certain improvements in the cracking and coking of hydrocarbon oils.

The invention is concerned with the coking of residual constituents from a pressure cracking operation and contemplates a combination cracking and coking process in which a condensate stock is subjected to a cracking temperature in a heating zone and the heated effluent therefrom subjected to counter-current contact with a heavy or residual stock in a reaction chamber wherein separation of vapors from liquid residue occurs and in which the residue is flashed to coke by means of its contained heat.

By having the heated condensate stock and the heavy or residual oil in counter-current contact in the reaction chamber a sufficiently high temperature may be maintained therein that the residue may be flashed to coke solely by its contained heat. Moreover, the refluxing to which the vapors are subjected while undergoing cracking in the countercurrent cracking chamber functions to prevent the delivery to the subsequent fractionator of certain heavy potential carbon-forming polymers with the result that the reflux condensate produced in the subsequent fractionator is suitable as charging stock to a recycling cracking zone. It is not necessary to subject the overhead vapors from the reaction chamber to any dephlegmating operation ahead of the fractionating zone in which the cycle condensate is formed. The overhead vapors from the reaction chamber may be subjected to fractionation to separate from the gasoline or naphtha distillate a higher boiling reflux condensate having a sufficiently low 90% A. S. T. M. distillation point and carbon residue that it may be subjected in a heating coil to high cracking temperatures and high rates of cracking per pass without encountering coking difficulties therein so as to effect conversion into high anti-knock gasoline constituents.

In accordance with the invention the condensate stock is passed through a heating coil and delivered to the lower portion of a reaction chamber into the upper portion of which a heavy oil or residual stock is introduced for cracking in counter-current contact with the rising vapors therein. Separation of vapors from liquid residue occurs in the reaction chamber and the vapors and residue are separately withdrawn. The reaction chamber is maintained at a high cracking temperature sufficient that upon the flashing of the residue a conversion to coke will occur. Liquid is prevented from accumulating in the reaction chamber by rapidly withdrawing it and de-

2

livering it to the coking zone wherein the pressure is lowered and the residue flashed to coke.

In the prior art practice coking has been accomplished with the aid of considerable quantities of hot vapors and gases and one of the principal difficulties encountered has been that occasioned by the priming of the coking drum. In this priming, potential coke-forming constituents are carried with the effluent vapors from the coking drum and create coking difficulties in vapor line and in the dephlegmating or fractionating portion of the system. In order to avoid this difficulty it has been necessary in the past to operate with relatively low charging rates to the coking drum and to maintain relatively high outage gauges therein, the outage gauge being the height of the space in the drum above the coke level. In accordance with the present invention, since the material directed to the coking chamber is essentially a liquid, the quantity of vapors and gases evolved from the coking chamber is greatly reduced with a consequent material diminution in priming tendencies. The practice of the invention thus makes possible the maintenance of high charging rates to the coking drum and high levels therein while avoiding priming, with the result that a maximum amount of coke is produced per coke drum cycle.

In practicing the invention the vapors from the counter-current reaction chamber are subjected to fractionation to obtain a reflux condensate which is cycled to the heating coil wherein it is subjected to cracking temperature and the heated effluent is discharged into the lower portion of the reaction chamber. The separated residue is withdrawn at temperatures adequate to support autogenous coking and is delivered into a lower pressure zone wherein it is coked by means of its contained heat. The vapors from the coking operation are subjected to a separate primary dephlegmation to form a heavy tarry condensate which is of highly aromatic character well adapted for fuel oil. This heavy condensate is either withdrawn as the product of the process or is combined with the hot residue withdrawn from the reaction chamber for coking. The dephlegmated vapors are subjected to dephlegmation with a charging stock such as topped or reduced crude and the resultant mixture of reflux condensate and unvaporized charging stock is directed to an upper portion of the reaction chamber for cracking in counter-current contact with the upwardly rising vapors therein.

For the purpose of more fully explaining the invention reference is had to the accompanying

drawing which is a diagrammatic drawing of an apparatus adapted for the practice of the invention.

In the apparatus illustrated the heating coil 10 is disposed in a furnace 11 adapted to heat the oil to a cracking temperature. The heated effluent passes through a transfer line 12 to a reaction chamber 13 which is vertically disposed and heat-insulated. As illustrated, the transfer line extends within the lower portion of the reaction chamber and terminates in an enlarged pipe or section 14 through which the heated products are discharged in an upward direction against a baffle 15. In practice with a three-inch transfer line the element 14 may be composed of a six-inch pipe. The products passing from the coil 10 to the reaction chamber 13 will consist largely of vapors and gases and upon being discharged through the enlarged pipe 14 against the baffle 15 an efficient diffusion of the vapors and gases is accomplished. A black oil or residual stock is introduced to an upper portion of the reaction chamber 13 through a line 16 which extends within the reaction chamber and terminates in a distributor or spray nozzle 17. The spray 17 is arranged to spray the liquid oil in a downward direction through the chamber so as to bring the liquid oil into intimate contact with the rising vapors. It is desirable to have an unobstructed space between the distributor 15 and spray nozzle 17 free from baffles or any other contact elements, since it is contemplated to maintain such elevated temperatures therein that injurious coking would take place if surfaces were presented upon which coke deposition could occur.

Separation of vapors from liquid residue takes place in the reaction chamber 13. The separated vapors pass through a vapor line 18 to a fractionating tower 19. This tower is provided with suitable vapor-liquid contact elements such as bubble trays and with suitable cooling and refluxing means. The vapors are fractionated in the tower 19 to separate the desired naphtha or gasoline fractions from higher boiling reflux condensate. This reflux condensate is recycled by a pump 20 through a line 21 to the heating coil 10. The gasoline or naphtha fractions pass from the tower 19 as a vapor to a condenser 22 thence to a distillate receiver or gas separator 23.

Liquid is prevented from accumulating in the reaction chamber 13 by the rapid withdrawal of liquid residue therefrom. In practice a very slight amount of vapor may be withdrawn with the liquid, an amount merely sufficient to insure that no liquid level is maintained in the reaction chamber. The residue is withdrawn through a line 24 and pressure-reducing valve 25 to a coking drum 26 wherein it is converted to coke by means of its contained heat. In practice a plurality of coking drums are employed so that while one is on stream the other or others may be down for coke removal or cleaning and thus continuity in the complete process maintained. The coking drums are suitably heat-insulated.

The vapors from the coking drum pass through a vapor line 27 to a primary dephlegmating zone. As illustrated, a tower 28 is provided having a lower section 29 and an upper section 30 separated by a trapout tray 31. The vapor line 27 communicates with the lower section 29 wherein the vapors from the coking operation are subjected to a separate primary dephlegmation. A limited amount of cooling is supplied to the dephlegmating zone 29 so as not to unduly reduce

the temperature and so as to obtain a condensate consisting of extremely high boiling constituents collected as a tarry condensate in the bottom of the dephlegmator. The tarry condensate is withdrawn through a line 32 and a portion thereof is continuously circulated by a pump 33 and line 34 back to the dephlegmating zone 29 so as to establish and maintain a continuous flow of liquid through the dephlegmating zone over baffles or vapor-liquid contact elements therein so as to thereby prevent coking. The function of this circulation is not to accomplish any cooling but merely to provide a flow of liquid through the dephlegmating zone which will prevent coking.

The dephlegmated vapors pass upwardly from the primary dephlegmating zone 29 to secondary dephlegmating zone 30 into which charging stock, such as crude petroleum or topped or reduced crude, is introduced by a pump 35 through a line 36. The resultant mixture of reflux condensate and unvaporized charging stock is withdrawn from the tray 31 through a line 37 and is directed by a pump 38 and line 39 thence through line 16 to the upper portion of the reaction chamber 13. If desired this mixture of condensate and unvaporized charging stock may be directed through a branch line 40 and heating coil 41 which may be conveniently disposed in the furnace 11. In the coil 41 the oil is subjected to a cracking temperature and the heated effluent is passed through a transfer line 42 to the line 16 for introduction to the reaction chamber 13.

Primary dephlegmated obtained from the coke still vapors may be withdrawn as a fuel oil product of the process. This product is of a high aromatic character and due to its solvent properties is particularly well adapted for blending purposes in the preparation of fuel oils. Instead of being utilized as fuel oil the primary dephlegmated may be directed by a pump 43 and line 44 to the coking drum 26 or to the transfer line 24 so as to combine it with the mixture of vapors and liquid which is passed from the reaction chamber 13 to the coking drum.

Naphtha or gasoline fractions are removed as vapors from the fractionating section 30 and passed to a condenser 45 thence to a receiving drum or gas separator 46.

In practicing the invention the cycle condensate is subjected to cracking temperature such as 1000° F.-1030° F. in the heating coil 10 and discharged into the reaction chamber 13 wherein the cracked products are contacted with the down-flowing residual stock. Superatmospheric pressures, such as 200-600 p. s. i., with cracking temperatures upwards of 900° F. are maintained in the reaction chamber. Liquid is prevented from accumulating in the reaction chamber 13 so that the coking of the residual constituents may be postponed until they reach the coking drum 26. It is not necessary to apply any heat to the coking drum other than that of the entering oil. By withdrawing the liquid residue from the reaction chamber at temperatures upwards of 920° F. and delivering it to the lower pressure coking chamber autogenous conversion to produce a marketable coke is readily accomplished. Temperatures of 920° F.-925° F. are recommended for the residue passing from the reaction chamber through the transfer line 24. The coking is conducted under reduced pressures approximating atmospheric pressure, preferably not over about 50 p. s. i. and at temperatures of about 850° F.

Separated vapors from the reaction chamber

13 pass through the vapor line 18 at a temperature of 900° F.-910° F. and the vapors are fractionated in the tower 19 under approximately the same pressure as obtains in the reaction chamber or, if desired, under a somewhat lower superatmospheric pressure. For example, with a pressure of 400 lbs. in the reaction chamber the fractionation may be conducted at approximately that pressure or the pressure may be reduced to an intermediate pressure such as 200-300 lbs. The fractionation is conducted so as to take overhead a distillate fraction of desired end point, such as a 400° F. end point fraction, and obtain a reflux condensate comprising the higher boiling constituents which is cycled to the cracking coil 10.

In the dephlegmator 29 only a relatively small amount of cooling is supplied which can be accomplished, for example, by cooling a small amount of the reflux condensate from tower 19 and refluxing it in the dephlegmator 29. It is desired to condense in this primary dephlegmator only the extremely high boiling constituents so that the bulk of the vapors will remain uncondensed and pass to the secondary fractionating section 30. Temperatures of about 800° F.-810° F. are maintained at the bottom of the dephlegmating zone 29 without coking due to the hot circulation accomplished by the pump 33. Due to the relatively small amount of reflux supplied to the dephlegmator 29 and to the circulation of the hot oil by the pump 33 there is a minimum temperature differential through the dephlegmator so that the uncondensed vapors pass to the dephlegmating section 30 at temperatures approaching 800° F. The residual charging stock introduced by the pump 35 is preferably passed in heat exchange with the hot products of the system prior to introduction to the dephlegmator 30 and the mixture of reflux condensate and unvaporized charging stock is withdrawn from the tray 31 at temperatures of about 750° F.-780° F. This mixture is either passed directly to the reaction chamber 13 through line 16 or is passed through the heating coil 40 wherein it is heated to temperatures of the order of 800° F.-900° F. before being introduced into the reaction chamber.

In the prior practice when using, for example, coke drums 40 ft. by 10 ft. in size it was necessary to maintain the coke drum outage gauge at about 23-24 ft., that is coke depths of 16-17 feet, in order to prevent priming and consequent coking in the primary dephlegmator. By means of the present invention the outage gauge may be reduced to as low as 15-17 feet, that is the coke depths increased to 23-25 feet, with a consequent increase in fresh charge capacity of some 30-50%.

While I have described a particular embodiment of my invention for purposes of illustration, it should be understood that various modifications and adaptations thereof, which will be obvious to one skilled in the art, may be made within the spirit of the invention as set forth in the appended claims.

I claim:

1. In the combination cracking and coking of hydrocarbon oils the process that comprises passing a condensate stock through a heating coil wherein it is subjected to a high cracking temperature, delivering the heated stream into the lower portion of a vertically disposed reaction chamber wherein separation of vapors from liquid residue takes place, introducing a stream of heated residual stock into an upper portion of the reaction chamber, subjecting resultant down-flow-

ing liquid and upwardly rising vapors to countercurrent contact in an unobstructed zone within the reaction chamber at cracking temperatures of upwards of 900° F. under 200-600 pounds pressure, withdrawing the separated vapors from an upper portion of the reaction chamber at a temperature of the order of 900° F., withdrawing the liquid residue from the lower portion thereof at a temperature of the order of 920° F. at a rate adequate to prevent the accumulation of liquid residue therein, delivering the withdrawn residue to a coking zone wherein the pressure is reduced to a low pressure not exceeding about 50 pounds and wherein a temperature approximating 850° F. is maintained by means of the hot residue introduced to thereby effect coking solely by the contained heat of the residue, subjecting said vapors withdrawn from the reaction chamber to fractionation to separate lighter products from higher boiling reflux condensate, cycling said reflux condensate to the aforesaid heating coil, subjecting evolved vapors from the coking zone to dephlegmation with a residual charging stock to form a resultant mixture of reflux condensate and unvaporized residual charging stock, passing said mixture of reflux condensate and unvaporized residual charging stock through a heating coil wherein it is heated to a temperature of the order of 800-900° F. and directing the heated mixture to the upper portion of the aforesaid reaction chamber as the residual stock introduced therein.

2. In the combination cracking and coking of hydrocarbon oils the process that comprises passing a condensate stock through a heating coil wherein it is subjected to a high cracking temperature, delivering the heated stream into the lower portion of a vertically disposed reaction chamber wherein separation of vapors from liquid residue takes place, introducing a stream of heated residual stock into an upper portion of the reaction chamber, subjecting resultant down-flowing liquid and upwardly rising vapors to countercurrent contact in an unobstructed zone within the reaction chamber at cracking temperatures of upwards of 900° F. under 200-600 pounds pressure, withdrawing the separated vapors from an upper portion of the reaction chamber at a temperature of the order of 900° F., withdrawing the liquid residue from the lower portion thereof at a temperature of the order of 920° F. at a rate adequate to prevent the accumulation of liquid residue therein, delivering the withdrawn residue to a coking zone wherein the pressure is reduced to a low pressure not exceeding about 50 lbs. and wherein coking is effected solely by the contained heat of the residue, subjecting said vapors withdrawn from the reaction chamber to fractionation to separate lighter products from higher boiling reflux condensate, cycling said reflux condensate to the aforesaid heating coil, subjecting evolved vapors from the coking zone to dephlegmation with a residual charging stock to form a resultant mixture of reflux condensate and unvaporized residual charging stock, passing said mixture of reflux condensate and unvaporized residual charging stock through a heating coil wherein it is heated to a temperature of the order of 800-900° F. and directing the heated mixture to the upper portion of the aforesaid reaction chamber as the residual stock introduced therein.

3. In the combination cracking and coking of hydrocarbon oils the process that comprises passing a condensate stock through a heating coil

wherein it is subjected to a high cracking temperature, delivering the heated stream into the lower portion of a vertically disposed reaction chamber wherein separation of vapors from liquid residue takes place, introducing a stream of heated high boiling constituents, formed as hereinafter specified, into an upper portion of the reaction chamber, subjecting resultant down-flowing liquid and upwardly rising vapors to counter-current contact in an unobstructed zone within the reaction chamber at cracking temperatures of upwards of 900° F. under 200-600 pounds pressure, withdrawing separated vapors from an upper portion of the reaction chamber at a temperature of the order of 900° F., withdrawing liquid residue from the lower portion thereof at a temperature of the order of 920° F. at a rate adequate to prevent the accumulation of liquid residue therein, delivering the withdrawn residue to a coking zone wherein the pressure is reduced and wherein coking is effected solely by the contained heat of the residue, subjecting said vapors withdrawn from the reaction chamber to fractionation to separate lighter products from higher boiling reflux condensate, cycling said reflux condensate to the aforesaid heating coil, subjecting the evolved vapors from the coking zone to a separate dephlegmation in a primary dephlegmating zone to form a heavy tarry condensate, subjecting resultant dephlegmated vapors to dephlegmation with a residual charging stock to form a resultant mixture of reflux condensate and unvaporized residual charging stock, passing said mixture of reflux condensate and unvaporized residual charging stock through a heating coil wherein it is heated to temperatures of the order of 800-900° F. and directing the resultant heated products to the upper portion of the reaction chamber to constitute the aforesaid high boiling constituents introduced thereinto.

4. In the combination cracking and coking of

hydrocarbon oils the process that comprises passing condensate stock through a heating coil wherein it is subjected to a high cracking temperature, delivering the heated stream into the lower portion of a vertically disposed reaction chamber wherein separation of vapors from liquid residue takes place, introducing a stream of heated high boiling constituents, formed as hereinafter specified, into an upper portion of the reaction chamber, subjecting resultant down-flowing liquid and upwardly rising vapors to countercurrent contact in an unobstructed zone within the reaction chamber at cracking temperatures of upwards of 900° F. under 200-600 lbs. pressure, withdrawing the separated vapors from the upper portion of the reaction chamber at a temperature of the order of 900° F., withdrawing the liquid residue from the lower portion thereof at a temperature of upwards of 920° F. and at a rate adequate to prevent the accumulation of liquid residue therein, delivering the withdrawn residue to a coking zone wherein the pressure is reduced and wherein coking is effected solely by the contained heat of the residue, subjecting said vapors withdrawn from the reaction chamber to fractionation to separate lighter products from higher boiling reflux condensate, cycling said reflux condensate to the aforesaid heating coil, subjecting evolved vapors from the coking zone to dephlegmation with a residual charging stock to form a resultant mixture of reflux condensate and unvaporized residual charging stock, passing said mixture of reflux condensate and unvaporized residual charging stock through a heating coil wherein it is heated to a temperature of the order of 800-900° F. and directing the resultant heated products to the upper portion of the reaction chamber to constitute the aforesaid high boiling constituents introduced thereinto.

JOSEPH MASON BARRON.
